UNITED STATES PATENT OFFICE

HARRY FOX, OF LOWELL, MASSACHUSETTS

UPHOLSTERY EDGE

Application filed October 19, 1928. Serial No. 313,469.

In the manufacture of articles of upholstery, more particularly those known as overstuffed, it has been customary to build up reinforced edges for the cushions and like parts, for this purpose the upholsterer progressively forming up a foundation over which the covering fabric is drawn.

The present invention relates to a pre-formed foundation material for such edges which may be cut to the length desired and the covering fabric drawn thereover, eliminating the necessity of progressively building up such a foundation and securing the fabric thereto as the article of furniture is being made, this being an expensive operation and requiring experience and great skill.

The present invention, therefore, has for an object the production of a thoroughly satisfactory foundation or "edge" from readily available materials and at small expense.

For a more complete understanding of this invention, reference may be had to the accompanying drawings in which

Figure 1 is a cross section of strips of fibrous material secured together preparatory to folding to form the desired edge.

Figure 2 is a similar view showing the use of different material.

Figures 3 and 4 are cross sections through the finished foundation edge showing the materials of Figures 1 and 2, respectively.

Figure 5 is a fragmentary section through a cushion showing one manner of using the edge.

Referring to Figure 1, at 1 is shown in cross section a relatively wide strip of fibrous material such as felt. Superposed centrally thereon is a much narrower strip 2 of the same or similar material, these strips being united centrally as by a line of stitching 3. The compound strip thus formed is folded together about the line of stitching 3, causing the edges of the strip 2 to be brought together as shown at 4 in Figure 3 and causing the narrower strip thus folded to be enveloped by the strip 1 whose marginal portions are brought together in face to face relation as along the lines 5 and fixed in this position beyond the folded strip 2, as by means of lines of stitching 6 and 7. The

narrower strip thus forms a core about which the wider strip is folded, causing the whole to present a substantially round bead 8 having a narrower extended portion 9 along one side thereof.

As the fibrous material most suitable for the purpose is made in sheet form, the core strip 2 cut therefrom is of rectangular cross section. The folding operation, however, causes the core to become substantially circular in cross section and at the same time wraps the relatively wide strip therearound, the line of the stitching 3 indenting the surface of the core strip and defining a natural line of fold about which it tends to bend when the edges of the strip 1 are brought together. Preferably the core strip, as shown, is of a width of about double its thickness, as when folded this produces a substantially circular core of a diametrical cross section about double the thickness of the strip.

In Figure 2, in place of using a felt strip, a strip of cheaper fibrous material, such as hair or the like, as at 10, reinforced as by a strip of burlap or other fabric 11 on one face, is used. As shown in this figure the wider strip 10 is provided with longitudinal lines of stitching 12 fixing the burlap or other fabric thereto. The narrow strip 15 may be made of similar material having the reinforcing fabric 16 thereon. These strips are fixed in superposed relation, as shown in Figure 2, the reinforcing fabric 11 being on the lower side of the strip 10 and preferably also the reinforcing fabric 16 adjacent to the upper face of the strip 10. These strips, fixed together as by the line of stitching 20, are then folded about this line, as shown in Figure 4, to cause the strip 10 to envelop the folded strip 15, the marginal portions of the strip 10 being then secured together in face to face relation as by means of the stitching 17 and 18.

The foundation or edge thus produced may be cut to the desired lengths and fixed to the upholstered article in position to have the outer fabric or covering material 21 drawn over the rounded bead portion 8, as, for example, as illustrated in Figure 5 in which one manner of using this strip is illustrated. It

is firm enough to properly shape the covering material but is not stiff, nor liable to breakage in service, nor will it take a permanent set when bent at any point as by pressure thereon by a portion of the body of the occupant of the chair or other article in which it may be incorporated, the felted material being inherently springy and tending to resume its normal condition.

10 Having thus described certain embodiments of this invention, it should be evident to those skilled in the art that various changes and modifications might be made without departing from its spirit or scope 15 as defined by the appended claims.

I claim:

1. An upholstery edge comprising a pair of superposed strips of fibrous material, one of said strips being wider than the other, a line 20 of stitching fixing the strips together between their side edges, said strips being folded longitudinally to cause the wider of said strips to envelop the narrower strip, and means for securing together the margins of said wider strip beyond the edges of said 25 narrower strips.

2. An upholstery edge comprising a strip 30 of fibrous material folded along a median line and stitched together back from the line of fold, and a core between the adjacent sides of said strip at said line of fold, said core comprising a single strip of fibrous material narrower than said first mentioned strip and folded along a median line.

3. An upholstery edge comprising a pair of strips of fibrous material, one being narrower than the other and fixed in superposed central relation by a line of stitches to the other, the edges of said wider strip being brought together to fold said narrower strip about the line of stitching and to envelop said narrower strip by said wider strip, and lines of stitching securing said edges outwardly of the edges of said narrower strip.

4. An upholstery edge comprising superposed strips of fibrous material, one of said strips being narrower than the other and of substantially rectangular cross section, said narrower strip being folded together about a median line to form a core and the other of said strips being folded lengthwise about said core to enclose the same, its folded portions beyond said core being secured together.

5. An upholstery edge comprising superposed strips of felted fibrous material stitched together along a median longitudinal line, one of said strips being narrower than the other and of rectangular cross section, said strips being folded together about the line of stitching with said narrower strip on the inner side of the fold and enclosed by the other of said strips, the folded portions of said other strip being secured together beyond said narrower strip.

6. An upholstery edge comprising super-

posed strips of felted fibrous material stitched together along a median longitudinal line, one of said strips being narrower than the other and of rectangular cross section of a width substantially twice its thickness, said strips being folded together about the line of stitching with said narrower strip on the inner side of the fold and enclosed by the other of said strips, the folded portion of said other strip being secured together beyond 75 said narrower strip.

In testimony whereof I have affixed my signature.

HARRY FOX.
